WRAPPER FOR USE IN HAIR WAVING
PROCESSES

William H. Joyce, Jackson Heights, N. Y.

Application July 14, 1933, Serial No. 680,381

3 Claims. (Cl. 132—36.2)

This invention relates to wrappers for enclosing wound strands of hair during the forming of permanent waves therein, and is an improvement over the construction of wrapper set forth 5 in my co-pending application filed May 18, 1933, Serial No. 671,678.

In the art of permanent waving of human hair, it is the practice to arrange the hair in strands or hanks, and tightly wind the same 10 upon individual curler rods, after which a strip of absorbent material which has been impregnated with a lotion or powder commonly used in the process of hair waving, is wound upon the wound hair, and the said strip of absorbent 15 material is enclosed in a moisture proof outer wrapper, so that when the curled hair and absorbent material are subjected to the action of heat by the heaters fitted over the respective wrapped curled hair, vapor will be produced 20 within the protecting jacket formed by the wrapper. Many objections are found to the present type of wrappers due to the escape of steam vapors therefrom which reduce the effectiveness of the hair waving process, and although skillfully wrapped, often results in scalp burns to the head of the person receiving the wave. Therefore, one of the main objects of the 25 invention resides in a combined pad and wrapper which will provide a sealed jacket for the wound hair to prevent the escape of vapors therefrom, and which may be sealed without the use of sealing clips and other extraneous devices.

Another feature of the invention resides in a 30 wrapper which may be easily and quickly cut down to adapt the same for the wrapping of the short ends of hair which is now accomplished by the use of a different style of wrapper than that used for the waving of relatively long hanks of hair.

A further feature of the invention over that set forth in the above copending application embodies the notching or slitting of the wrapper inwardly from one of the longitudinal edges 45 rather than from one of the side edges. By so arranging the notch or cut, I am able to materially increase the sealing qualities of the wrapper when wound upon a hank of hair to be waved.

50 A further object of the invention is the provision of a combined hair curling pad and wrapper in which the pad which is first wound upon the wound hair to be waved receives at least one winding of the wrapper to secure the pad in tight wound condition before the same is re-

leased by the hands of an operator to hold in the end sealing flap which is necessary before the complete winding of the wrapper.

A still further object of the invention is the provision of a wrapper for use in permanent hair waving having the above features which is simple and inexpensive of construction, and easy and quick to apply to the wound hair preparatory to the subjection of the same to heat.

With these and other objects in view, the invention resides in the certain novel construction, combination and arrangement of parts, the essential features of which are hereinafter fully described, are particularly pointed out in the appended claims, and are illustrated in the accompanying drawings, in which:

Figure 1 is a perspective view of the preferred embodiment of my invention with parts broken away.

Figure 2 is a plan view of the improved wrapper associated with a hank of wound hair to be waved.

Figures 3, 4, 5, and 6 are plan views showing the wrapper in various positions during the winding of the same upon a hank of hair to be waved.

Figure 7 is a plan view of a modified form.

Figure 8 is a plan view of a wrapper for the winding of hair ends which is cut from a wrapper of the preceding construction.

Figures 9, 10, and 11 are plan views of various modifications.

Referring to the drawings by reference characters, and more particularly to the form of the invention shown in Figures 1 to 6 inclusive, the numeral 10 designates a rectangular shaped pad of absorbent material, such as felt, flannel or the like which is impregnated with or dipped in a hair treating solution prior to the application of the wrapper to the hair to be waved. The 35 pad may be of a single thickness of material, or formed of a single piece doubled upon itself to provide two thicknesses. The pad 10 is attached to one side of the wrapper or outer covering 11 in a manner presently to be described.

The wrapper or outer covering 11 is of substantially rectangular shape but is cut to provide right angularly disposed joining extension portions 12 and 13 at one end and at one of the adjacent longitudinal sides. The transverse 50 and longitudinal edges of the wrapper are straight as are the side edges of the extension portions, while the end edges of said extension portions are straight and at right angles to the adjoining side edges.

The end edge of the extension portion 12 terminates inwardly of the longitudinal edge 14 of the wrapper, and to which edge 14, the pad 10 is secured by a line of stitching 15, one end 5 of the pad being even with the end edge of the wrapper from which the portion 12 extends, while the other end of the pad terminates short of the opposite end of the said wrapper.

The wrapper or covering 11 comprises an outer sheet of aluminum or tin foil 16, and inner sheets of paper 17-17. The sheets of paper 17 may be formed of a single piece folded upon itself along one of the longitudinal edges or may be of two separate sheets held together by the stitching 15 which passes through the sheets of paper as well as the foil sheets 16. Also if desired, the foil sheet 16 may be interposed between the paper sheets, and furthermore only one paper sheet may be associated with the foil sheet if desired. By associating a foil sheet with the paper sheet or sheets I provide a moisture proof wrapper which will not be chemically affected by the hair treating lotion or substances carried by the pad and furthermore the foil or other material having the same characteristics provides the wrapper with the necessary pliability to retain any shape to which it is formed.

The inner end of the extension portion 12 along the adjacent sides of the wrapper body 30 11 is cut inwardly or notched as at 18, the inner end of which is rounded as at 19 and it is the rounded closed end of the notch which receives the inner end of the wound hank of hair during the winding of the wrapper upon the wound hair.

In practice, assume that it is desired to wrap a wound hank of hair H without the aid of a clip commonly used for securing the wrapper in position thereon. The pad 10 is first dipped into a liquid or lotion to prepare the same for chemical action, and after the hair has been wound in the usual manner upon a curling stick A, and the ends of the strand or hank of hair are secured thereto by tying as at B, the pad is placed 40 against the wound strand as shown in Figure 2 with the extension portion 12 facing downward. The pad is applied adjacent the inner end of the wound hank, and wound therearound, the winding operation being continued until the rounded 45 end 19 of the notch reaches the inner end of the hank of hair H. During this initial winding operation, a portion of the wrapper, and at least one convolution of the same is wound about the pad 10 to enclose the same and securely hold the pad in its wound condition. This position is clearly shown in Figure 3 of the drawings, after 50 which the extension portion 12 is folded inwardly over the body of the wrapper and a portion of one end of the extension overlaps the partially wound wrapper. This inward portion of the portion 12 provides a sealed joint between the wrapper and the base of the hank of hair, and after the folding operation, the winding of the wrapper is completed as illustrated in Figures 5 and 6 of the drawings. This inwardly folded extension 12 is maintained in folded condition by the inherent qualities of the sheet of tinfoil 16 and when fully wrapped as shown in Figure 6, the extension portion 13 affords sufficient material to complete the wrapping of the neck or base of the hank of hair without adding bulkiness throughout the entire length of the jacket. Due to the pliable nature of the foil sheet 16, the folded end of the wrapper is compressed and the seal maintained about the inner 70 75

end of the hank of hair to prevent leakage of steam vapors from the jacket when the same are subjected to the action of heat produced by the heaters adapted to be fitted over the wrapped hair to be waved.

This construction of wrapper is especially adapted for use without requiring clips for maintaining the seal at the base of the hank of hair, although if clips are desired, the wrapper may be wound upon the hair without the inward folding of the extension portion 12 and this provides a skirt portion at the inner end of the wrapper to which the clip may be attached.

In Figure 7 of the drawings, the numeral 20 designates a modified form of wrapper wherein the pad 21 is secured to one of the edges of the wrapper body 22, which like the construction shown in the preceding form includes joined extensions 23 and 24. The inner end of the extension 23 terminates short of the longitudinal edge of the wrapper body to which the pad 21 is secured and the wrapper body 22 is provided with a dotted line 25. In this form of wrapper, the extension portion 23 is folded inwardly similar to the inward folding of the portion 12 of the preferred form and the wrapper wound in a similar manner. This construction provides a relatively tight seal between the base of the hank of hair and the wrapper when used as a no-clip pad and when used in association with a clip, the extension portion 23 is wound upon the hank of hair and affords a skirt portion to which the clip may be attached.

In the waving of hair, it is customary to employ different size pads, that is one size for the treating of long hanks to be waved, and others to be wound upon the ends or short lengths. Thus by cutting the pad 20 along the dotted lines to the shape of the pad shown in Figure 8, a smaller pad is produced which may be used for winding upon the hair ends.

In Figure 9 of the drawings, a still further modified construction is shown wherein the wrapper body 26 is similar to that shown in the preferred form with the exception that the inner end of the extension portion 27 is provided with a substantially V-shaped cut out 28 which provides a restricted entrance to a circular opening 29.

In Figure 10, the wrapper body 30 is formed with an end extension 31, the inner edge of which is provided with an inwardly extending slit 32 which enters into a rounded opening 33.

In Figure 11 the wrapper body 34 includes an extension portion 35, the end of which is slit 55 inwardly on a straight line as at 36.

The various modified constructions shown in Figures 9, 10 and 11 perform substantially the same function and result as that set forth in the preferred form previously described.

While I have shown and described several modified constructions of my invention, I wish it to be understood that such other changes or modifications may be resorted to if desired as come within the scope of the appended claims.

Having thus described the invention, what I claim as new and desire to secure by Letters Patent of the United States, is:—

1. A wrapper for enclosing a wound strand of hair during a hair waving process comprising a substantially rectangular shaped flexible pliable wrapper body adapted to maintain a deformed condition when wound, an absorbent pad secured to one of the longitudinal edges of said wrapper body, an extension flap provided at one

end of said wrapper body, the inner end of said extension flap terminating short of that longitudinal edge of said wrapper body to which said pad is secured, the flap being slit inwardly from its inner end to enable the infolding of the inner end of the flap about the base of the strand of wound hair to be enclosed by the wrapper.

5 2. A wrapper for enclosing a wound strand of hair during a hair waving process comprising a substantially rectangular shaped flexible pliable wrapper body adapted to maintain a deformed condition when wound, an absorbent pad secured to one of the longitudinal edges of said wrapper body and positioned with one end of said pad flush with one end of said wrapper body, an extension flap provided at one end of said wrapper body on that end with which said pad is flush, the inner end of said extension flap terminating short of that longitudinal edge of said wrapper body to which said pad is secured, the flap being slit inwardly from its inner end in line with the adjacent end edge of said wrapper body to en-

able the infolding of the inner end of the flap about the base of the strand of wound hair to be enclosed by the wrapper.

3. A wrapper for enclosing a wound strand of hair during a hair waving process comprising a substantially rectangular shaped flexible pliable wrapper body adapted to maintain a deformed condition when wound, an absorbent pad secured to one of the longitudinal edges of said wrapper body and positioned flush with one end of said wrapper body, an extension portion provided on said wrapper body on that end with which one end of said pad is flush, the inner end of said extension portion terminating short of the longitudinal edge of said wrapper body to which said pad is secured, and a notch extending inwardly from the inner end of said extension portion in line with the adjacent end edge of said wrapper body, the inner end wall of said notch being rounded, substantially as and for the purpose specified.
